UNITED STATES PATENT OFFICE

124,776

DESIGN FOR A DRESS ENSEMBLE

Alfred O. Gilbert, Chicago, Ill.

Application November 26, 1940, Serial No. 96,843

Term of patent 3½ years

To all whom it may concern:

Be it known that I, Alfred O. Gilbert, a citizen of the United States, residing in Chicago, in the county of Cook and State of Illinois, have invented a new, original, and ornamental Design for a Dress Ensemble, of which the following is a specification, reference being had to the accompanying drawing, forming part thereof.

I claim:

The ornamental design for a dress ensemble, substantially as shown.

ALFRED O. GILBERT.
